LEON J. LE PONTOIS, OF LAKWOOD, OHIO, ASSIGNOR, BY MESNE ASSIGNMENTS, TO THE TEAGLE COMPANY, OF CLEVELAND, OHIO, A CORPORATION OF OHIO.

COMBINED IGNITION AND LIGHTING GENERATOR.

1,276,085.

Specification of Letters Patent. Patented Aug. 20, 1918.

Application filed June 28, 1915. Serial No. 36,672.

To all whom it may concern:

Be it known that I, LEON J. LE PONTOIS, a citizen of the Republic of France, residing at Lakewood, in the county of Cuyahoga and 5 State of Ohio, have invented certain new and useful Improvements in and Relating to Combined Ignition and Lighting Generators, of which the following is a specification.

This invention relates to a combined generating unit for the generation both of direct low tension current and of high tension current for use on motor vehicles having internal combustion motors, the high tension current being adapted for ignition purposes 15 and the low tension current for lighting and the like.

The general introduction in the motor vehicle chassis of the direct current generator for such purposes as electric lighting, 20 electric horn operation and for charging electric storage batteries has been responsible to a large extent for the return to so-called battery ignition for the internal combustion motor through the intermediary of an induction coil.

In some cases the primary circuit breaker and high tension current distributor for the battery system have been incorporated in a unitary structure with the direct current 30 dynamo, the breaker and distributor being operated from the armature shaft at the proper time for the ignition of the internal combustion motor, and even the induction coil itself has been incorporated in this unitary structure. This combination results in a saving of space under the motor hood and weight, as compared with a system including a direct current generator and an independent magneto of the permanent magnet type 35 for ignition purposes. The battery system as known today does not possess the heat value of igniting sparks, and essentially the sustained heat value, which is inherent in the characteristic high tension spark generated by a direct high tension magneto of the permanent magnet type. In order to obtain thorough and rapid ignition within the cylinder of an internal combustion engine, so indispensable for the efficient conversion 45 of the energy of the combustion of the fuel into mechanical work, the resistance that the dielectric opposes to current flow between

the spark terminals in a cylinder must first be broken down by puncturing the dielectric by a high tension spark and the current 55 value at the instant of puncture maintained or increased during the period of time necessary to insure the ignition of as much of the combustible material as is required to secure the most beneficial and efficient results. For 60 this reason the direct high tension magneto may be said to generate a spark having a sustained current value during the period of time necessary for thorough ignition as contra-distinguished from and preferable to 65 battery ignition in which current in the secondary winding of an induction coil is induced merely by the collapse of a magnetic field and without the expenditure upon the magnetic circuit of the mechanical energy 70 required to give such sustained current value to the resulting ignition spark. However, the bulk presented by the permanent magnets of a high tension magneto of the permanent magnet type and the expense of 75 construction is generally such as to render commercially impractical its combination with a direct current generator in a unitary structure, and the expense of a separate direct current generator with its driving connections to the motor and an independent high tension magneto with its driving connections to the motor, as compared with the expense of a direct current generator and the necessary mechanism for connecting up 80 and operating one of the well known forms of battery system, is such as to make in many installations the expense of the former practically prohibitive.

One of the objects of my invention has 90 been to provide a combined generating unit for a system of direct current generation and high tension current generation which may be encompassed in substantially the space occupied by the so-called battery systems of today or even in smaller space, and in which undesirable characteristics of such battery systems will be avoided and desirable characteristics of the direct high tension magneto systems incorporated, and in 95 which the high tension sparks generated will have sustained values as compared with the ignition sparks with substantially unsustained values as produced with the so-called

battery systems using induction coils; or in other words my improved system will produce sparks having the same time-temperature characteristics as those produced by the 5 so-called direct high tension magnetos, namely a temperature that suddenly rises to a high value is maintained at this or a higher value for an appreciable time necessary to insure proper and efficient ignition and then drops 10 relatively slowly to its initial state.

It has also been one of the objects of my invention materially to reduce the current consumption used for the generation of ignition sparks as compared with the current 15 consumption of the so-called battery system.

As a matter of fact at the present time battery systems may be constructed and installed at considerably less expense than any of the well known magnetos of the permanent magnet type, and a battery system is 20 likely to start the motor at a lower engine speed than a high tension magneto system, since with the latter the value of the spark is largely dependent upon speed of rotation.

25 while in the battery systems the spark value is highest at low speeds of rotation of the crank shaft of the engine. One of the objects of my invention has been to design a high tension ignition generator, the high 30 tension current characteristics of which are such as to avoid the objections of low current values at low speed incident to high tension magneto systems by providing a much higher flux density than can be obtained 35 in a commercially practical manner by the use of permanent magnets for field excitation. It will be understood that the higher the speed necessary to generate an igniting spark of sufficient value to properly 40 start the motor, the more energy is consumed in the rotation of the crank shaft and where an electrical or mechanical starting device is employed for this purpose, the less energy required to rotate the crank shaft for 45 starting purposes, the better. I have therefore invented an apparatus and system in which ignition sparks of sustained value will be generated at low speeds so as to insure easy motor starting.

50 Another object of my invention has been to correlate and coordinate the elements of the generator so that they will be both efficient and durable in connection with the ignition of internal combustion motors running at relatively high speeds and having a relatively large number of cylinders. With the so-called high tension magneto of the permanent magnet type serious mechanical and electrical difficulties have been 55 encountered in its use with high speed multiple cylinder engines. With my invention it will be understood that the speed of rotation of the rotatable parts of my ignition generator may be materially reduced over 60 those necessary with the high tension mag-

netos of today in order to get efficient and proper ignition for multiple cylinder motors at all speeds.

Another object of my invention has been to produce a combined generating unit making possible a system for generating and distributing sustained high tension sparks, the total weight and production cost of which will be materially less than the total weight and cost of the same system when provided 70 with an ignition generator of the self-contained high tension permanent magnet type. And in view of the fact that permanent magnets are not used and not required in my system and apparatus, the construction, 80 shaping, assembling and cost of necessary parts is minimized.

Figure 1 is a vertical longitudinal section of the combined unit along the axis of the rotors.

Fig. 2 represents an end view showing the breaker mechanism of the high tension spark generator, the breaker casing cover being removed.

Fig. 3 is a section on the line 3—3 of Fig. 90 1, showing one of the collector rings and contact shoes of the direct current generator.

Fig. 4 is an end view of the high tension spark generator with end plate removed and 95 the rotor shown in section.

Fig. 5 is a vertical section on the line 5—5, of Fig. 1.

Fig. 6 is a vertical longitudinal section showing the magnetic field structures of the 100 direct current generator and of the high tension spark generator built as a unit.

Fig. 7 shows the rotors of both generators assembled as a unit.

Fig. 8 is an electrical connection diagram 105 of the low tension direct current circuit.

Fig. 9 is a schematic diagram of the electrical connections of the spark generating coils and high tension circuit.

In the drawings, 1 indicates as an entirety a field magnet frame structure and 2 a rotor mounted therein. The frame structure in the illustrated embodiment of my invention is made of three castings, 1', 1^b, and 1^b, suitably joined and held together by 110 bolts 3, and a group of iron lamineæ 1^c positioned in the open end of the section 1^b and held there by bolts or screws 3'. Each of the sections 1', 1^b, has an annular, axially disposed polar projection 4, 5, respectively. 115 These polar projections are alined and each is surrounded by an exciting winding 6, 6', respectively. The rotor 2 includes a shaft 2' suitably mounted at one end in an anti-friction bearing 7 positioned in the adjacent 120 section 1' of the frame 1, and at its opposite end in an anti-friction bearing 7' positioned in an end plate 8 secured by the bolts or screws 3' to the section 1^b.

Secured to the shaft 2' is a structure of 130

magnetizable iron, or steel, preferably of high magnetic permeability, having a section 2^a provided near its center with a group of annular laminæ 2^b having polar surfaces 2^c disposed to rotate in close proximity to the polar surfaces 1^d of the field structure.

At either side of the section 2^a the rotor has a cylindrical extension 2^e, 2^{e'}, each having polar surfaces 2^f, 2^{f'}, respectively, disposed to rotate in close proximity to the adjacent polar surface 1^e, 1^{e'}, of the annular polar projections 4, 5, respectively. At 2^g the rotor is reduced in size to form a core for an exciting winding 10 and at 2^h is shaped to receive a laminated flux distributing-section 11.

12 are collector rings, a series of them with each ring of each series suitably insulated from the others, and from the rest of the 20 rotor, is disposed at either side of the section 2^b, as indicated. Each series of collector rings with the necessary insulation may be held together in any suitable manner as by bolts or screws 12' screwed into the adjacent 25 side of section 2^b and suitably insulated from the collector rings as indicated in the drawing, 13 being end plates mounted upon the section 2^a for positioning the collector rings relative thereto.

30 14 indicate electric conductors, preferably of copper, each extending through and being insulated from the laminated section 2^b. These conductors 14 are preferably arranged about the axis of the rotor in sets, each set 35 consisting of three conductors 14, each said conductor of each set being disposed about the axis of the rotor 120 degrees from the other two conductors of said set and the three conductors of each said set being connected electrically in parallel by electrically 40 connecting the ends of each trio of said conductors 14 at opposite sides of the section 2^b to corresponding collector rings 12 in each of the series thereof at either side of the 45 said section 2^b. As shown in Fig. 1 the uppermost conductor 14 is electrically connected at its opposite ends to the nearest collector rings 12 in each of the series of collector rings at either side of the section 2^b. 50 The next trio of conductors 14 will be connected to the next pair of collector rings and so on about the periphery of the section 2^b. The lowermost conductor 14, illustrated in Fig. 1, is shown connected to a pair of rings, 55 each of which is disposed near the middle of each series.

For the purpose of collecting current generated in the conductors 14, I have provided groups of collecting devices preferably arranged at diametrically opposite sides of the rotor 2. Each of these groups of collecting devices preferably consists of a plurality of collecting bars and contact shoes, each group being suitably insulated from the field structure 1. For example, I have shown in the

drawings each group of collecting devices to consist of a plurality of bars 15, preferably of copper, the innermost bar of each group being suitably insulated from the field structure to which it is separately secured by 70 means of a binding plate 16 and a screw 17, which screw passes through said plate and each of the bars 15 of the group from which it is laminated and is screwed into the section 1^a of the field structure. At its in-turned end or ends, each of the bars 15 carries a pair of pivotally mounted contact shoes or brushes 19, preferably made of copper. 18 are insulating blocks by means of which each binding plate 16 is insulated 80 from the field magnet structure.

19' are springs each secured at its outer end to the adjacent insulating block 18 and having its inner free end bearing against the upper surface of the adjacent contact shoe 19 so as normally to press the latter into engagement with the collector ring with which it is adapted to co-operate.

19 The contact shoes 19 at the inturned end of the innermost bar 15 of the upper group 90 engage with the adjacent innermost ring of the series of rings on the same side of the laminated section 2^b. The other end of this bar is connected with the terminal socket 20 carried by the adjacent insulating block 18. 95 The electrical circuit from the said ring in the left hand group is completed to the corresponding ring in the right hand group by a set of three conductors 14, connected as aforesaid, and from that point the circuit is extended or continued through the brushes 19 at the right hand side of the laminated section 2^b on the innermost bar 15 of the lower group through said bar to the brushes carried by it on the left hand side of said 100 laminated section 2^b and which latter pair of brushes make contact with the second ring 12 in the left hand series of collector rings, which second said ring is connected by a set of three conductors 14 to the second ring 105 in the right hand series, which latter ring in turn is engaged by brushes 19 on the adjacent end of the next to the innermost bar 15 in the upper group. This method of connection is followed out until finally the circuit through the machine reaches the uppermost bar 15 of the upper group, which bar has electrical contact with the terminal socket 21 carried by the adjacent insulating block 18, thereby completing the electrical 110 circuit within the machine.

115 At the ignition current generating end of the machine, each laminæ 1^c of magnetizable metal has two pairs of polar projections diametrically opposed, one pair being indicated by 22, 22', and the other by 23, 23', the former having polar surfaces 22^a and the latter polar surfaces 23^a, all of these polar surfaces being arranged in the arc of the circle struck from the axis of the shaft 120 125 130

2' as a center and being closely disposed to the polar surfaces 11^a of the laminated inductor rotor section 11.

24 are high tension generating windings 5 or coils each comprising preferably an inner section 24' of relatively coarse wire and outer section 24^a of relatively fine wire.

Any suitable and well known type of circuit opening and closing mechanism may be 10 employed for periodically closing and opening the circuits of each of the primary windings 24', 24', and likewise any well known type of distributor for distributing high tension current impulses from the secondary 15 windings 24^a, 24^a, to the cylinders of the motor in proper sequence may be used. For the purpose of illustration I have shown a circuit opening and closing mechanism indicated as an entirety by 26 and comprising 20 a box 27 mounted within the end plate 8 as shown at 27' and a stationary electrode 28 and movable electrode 29 arranged within said breaker box 27. The stationary electrode 28 may be carried by a terminal plate 25 30 insulated from the breaker box 27 and secured thereto by screws 31. The movable electrode 29 may be carried at one end of the breaker arm 32, which, intermediate its ends, at 33 is pivoted to the breaker box 27. The 30 other end of the breaker arm carries a cam contact shoe 34. A spring 35 bearing at one end against the breaker box and at its other end against a lug 36 on the breaker arm 32 serves normally to press the movable 35 electrode 29 into engagement with the stationary electrode 28. 37 is a cam suitably secured to the adjacent end of the shaft 2' and adapted to co-act with the breaker shoe 34 periodically to permit the closing and 40 effect the opening of the electric circuit through the electrodes 28 and 29. 38 is a shifting rod for angularly adjusting the breaker box to vary the instant of ignition for spark advance and retard purposes in 45 connection with the operation of a hydro-carbon motor. 39 is a condenser suitably carried by the magnetic frame structure. One terminal of this condenser is electrically connected to the electrode 29 and the other 50 terminal is grounded, as shown in Fig. 9.

In order to avoid a complication of lines I have not illustrated any of the well known types of distributor, which readily may be applied by one skilled in the art in a system embodying my invention.

40 is a secondary cell or cells or storage battery. This is connected with the terminals 20 and 21 so as to receive direct current from the generator. 41 is an automatic, 60 electro-magnetically actuated cutout, of any well known construction, arranged in the circuit between the direct current generator and the storage battery. The exciting winding 10 preferably is connected in parallel 65 with the storage battery 40 and the termi-

nals 20 and 21 of the direct current generator, a switch 42, as shown in Fig. 8, serving to permit the closing and opening of this circuit, as desired.

The field exciting coils 6, 6, may be electrically connected together in any suitable manner. I have illustrated them as connected directly across the generator terminal as shown in the diagram Fig. 8.

43 indicates an external working circuit, 75 illustrated as a lamp load, a switch 44 serving to cut it in or out as desired.

The operation of the combined generating unit in a system such as is contemplated will be readily understood. When it is desired to 80 start the hydro-carbon motor with which the system may be connected, the circuit from the battery 40 through the exciting winding 10 should be closed. If a switch, such as the one indicated at 42, is employed, 85 it should be actuated to close the circuit. Current will then flow from the battery 40 through the exciting coil 10 and set up the field which is the function of this particular coil. Then if the hydro-carbon motor be 90 actuated, the electric circuit through the primary windings 24' will be closed by the breaker 26 through the electrodes 28, 29, and then opened between these electrodes. I prefer to effect this closing and opening 95 when the current generated in the primary is due to a decrease of the density of magnetic flux threading through the coil, which according to Lenz law is a current which has the tendency to oppose such decrease of 100 density and consequently the magneto-motive force of this current tends to prevent the decrease in flux threading through the coil. When the flux distributor 11 has reached a certain point in its cycle of rotation, the circuit of each coarse wire winding 105 24' is suddenly opened by the action of the cam 37 moving the breaker arm 32 so as to interrupt the circuit between the breaker electrodes 28 and 29, whereupon owing to 110 the interruption of the current a sudden flux decrease takes place and a high tension voltage is set up across the terminals of each spark plug 50, then in the electric circuit of a secondary ignition winding 24^a. This 115 voltage reaches such a value that it punctures the dielectric between the terminals of the spark plug and causes a spark to jump therebetween. The flux decrease through each winding 24 continues, due to 120 the increasing reluctance of the magnetic circuit through the coil produced by the further movement of the flux distributing section 11 away from the polar surfaces which it has just traversed, to accomplish 125 which mechanical energy must be supplied by the driving mechanism and accordingly the arc formed between the terminals of the spark plug is sustained or maintained for a sufficient period of time to insure proper and 130

complete combustion of the gases within the engine cylinder.

Purely for the purposes of illustration, I have shown in the drawings a system 5 adapted to deliver two igniting sparks simultaneously within the same cylinder, using two coils, one breaker and a single condenser for this purpose, but it is to be understood that where but a single spark 10 in the cylinder is desired at a given instant, one coil will suffice and the other may be discarded. In using two coils as shown in the drawings, I prefer to connect them in a series, as illustrated in Fig. 9.

15 When the system is first started in operation, necessarily the voltage of the direct current generator, that is the voltage at the terminals 20 and 21, will be relatively low, and the electromagnetic cutout 41 should 20 be radiated so that it will not close the circuit between the direct current generator and the battery 40 until the voltage of the generator is superior to or at least equal to the voltage of the battery. During the operation of the system should the direct current generator stop delivering the necessary voltage for any reason, the automatic relay 25 41 will open the circuit between the direct current generator and the battery 40, so that 30 the battery 40 may continue the excitation of the coil 10 and thereby obviate a breakdown or discontinuance of proper operation of the ignition circuit.

It will be noted that the low tension direct 35 current generator is of the homo-polar type. I have purposely selected it because it lends itself readily to regulation of voltage at various speeds merely by proper field excitation, avoiding at the same time brush 40 sparking and armature re-action incident to certain other types of electric generators.

Each of the exciting windings 6, 6', sets 45 up a field in parallel with the other, so that two magnetic fields in parallel flow from opposite directions through the mass of the rotor between said exciting windings, through the enlarged laminated section 2^b of the rotor, thence to the center pole of the frame and back in opposite directions to the 50 cores of the said coils 6, 6', respectively.

The exciting winding 10 may be held in position in any suitable manner, as by ears or lugs 10' suitably secured to the coil and detachably connected to the adjacent wall of 55 the section 1^b by screws 10^a, as shown in Fig. 4. This exciting winding 10 sets up a magnetic circuit through the adjacent part of the rotor as a core, the adjacent end of the section 1^b, laminated section 1^c, thence in 60 either one of two paths between polar surfaces 22^a, 22^b, or 23^a, 23^b, to the laminated flux distributor 11 and back to the core of the coil.

It further will be noted that the combined 65 low tension direct current generator

and high tension current generator are combined in a single compact structure having elements in common co-operating to support parts of each generator properly relative to other parts thereof, the frame and rotor in 70 particular being common to each part of the apparatus and each having a distinct function in connection with each part. The current for exciting the winding 10 may be drawn from the low tension generator or 75 from any suitable source of direct current supply.

It further will be noted that the magnetic field structure is built in three sections. The middle section, 1^a, as shown in Figs. 3, 80 5 and 6, substantially prismatic in shape outside, is cylindrical inside, and machined so as to form a cylindrical polar surface, at its center and annular recesses, or sockets at each end, apertures 1^a' are formed in the 85 upper and lower walls so as to permit the introduction of contact shoes within the structure, as shown in Fig. 3. The end plates 1' and 1^b are fitted at each end of this middle section 1^a and bolted to it so as to 90 form a rigid structure, care being taken that the end plates fit tightly against the end surfaces of the middle section, so as to form a good magnetic joint.

It will be noted that the exciting winding 95 10 is connected in parallel with the battery and the brushes of the direct current generator. When the generator voltage exceeds the battery voltage, the cutout 41 will close and the generator will excite the winding 10 100 and whatever surplus current is generated by the direct current generator over and above that necessary to excite the winding 10 will be delivered to the storage battery 40. Should the circuit be for any reason interrupted so as to cut out the direct current 105 generator, the battery will deliver the necessary current to the exciting winding for field excitation purposes. During the operation of the internal combustion motor, 110 should the battery for any reason be disconnected, leaving in circuit the exciting winding and the direct current generator, the latter will energize the exciting winding sufficiently for the purposes of producing the 115 necessary ignition sparks.

It further will be noted that upon the opening of the primary circuit, when the ignition generator is in operation, the induced electro-motive force in the secondary is largely due to the collapse of the field set up by current flowing in the primary. This induction takes place practically instantly and is supplemented by the mechanical work done by the rotor in the magnetic field, and 120 the high tension spark thus produced between the terminals of the spark plug is sustained or augmented in value by the further collapse of a field within the coil 125 due to the mechanical rotation of the flux 130

distributer, the mechanical work necessary to cause this rotation being provided by the internal combustion motor.

It will be found that with a system embodying my invention, such as illustrated and described herein, a relatively low value of exciting current is required for exciting the coil 10 requisitely to effect the generation in the high tension circuit of the desired value of spark. In fact I have found the value of the exciting current required to be many times less than that now used in the principal battery ignition systems on the market.

15 I have found the use of an exciting coil in an ignition generator enables me to obtain a shorter and lighter magnetic circuit, a higher flux density and smaller cross-sectional area of the magnetic circuit, than is possible where permanent magnets are used, at the same time insuring that the total flux of the magnetic circuit is sufficient in amount to insure satisfactory spark generation at relatively low speeds.

20 25 It further will be noted that the combined unit, that is the direct current generator and high tension current generator combined, is relatively compact and of simple construction. But a single rotor is required for the purposes of effecting the generation both of the low tension direct and the high tension pulsating current. My invention lends itself admirably to use in such a combined unit. Furthermore, by its use 30 35 a great saving of space, number of parts and weight is effected over existing systems having the same high tension current wave forms.

40 45 To those skilled in the art of making mechanism of the class described, many alterations in construction and widely differing embodiments and applications of my invention will suggest themselves, without departing from the spirit and scope thereof. My disclosures and the descriptions herein are purely illustrative and are not intended to be in any sense limiting.

50 55 The term "direct current", or "direct current generator", as used herein is to be understood as comprehensive of a unidirectional current or means for generating unidirectional current.

The claims which I make in the present application relate to the improved combined generating unit *per se*, claims relating to the improved ignition system, and parts thereof, being presented in my copending application Serial No. 36,673.

60 65 Also, the subject-matter disclosed in the present application, both with respect to the generator *per se* and with respect to the system, has certain features in common with the subject-matter of my co-pending application Serial No. 124,827, filed October 10, 1916, as a division of application Serial No.

596,117, filed December 7, 1910, and said common features are claimed in the said divisional application.

What I claim is:

1. A single unit combined direct current and high tension ignition current generator, comprising a unitary field structure, separate exciting windings for the direct and ignition currents, respectively, separate generating windings for the direct current and high tension ignition current, respectively, and a single rotor for expending mechanical energy in the fields interlinking with said generating windings for the production of electro-motive force therein. 70 75

2. In a single unit direct current and high tension ignition current generator, the combination of a unitary field structure, exciting windings therefor, separate generating windings for direct current and high tension ignition current, respectively, a rotor mounted in said frame, common to all of said windings and adapted to expend mechanical energy in the fields interlinking with said generating windings for the production of electro-motive force therein, and a circuit breaker for said high tension winding actuated by said rotor. 80 85

3. In a single unit direct current and high tension ignition current generator, the combination of a unitary field structure, exciting windings therefor, separate generating windings for direct current and high tension ignition current, respectively, and a rotor common to all of said windings, 90 95 mounted in said structure and serving to expend mechanical energy in the field interlinking with said high tension generating winding during the generation of a high tension current impulse. 100 105

4. In a single unit direct current and high tension ignition current generator, the combination of a unitary field structure, exciting windings therefor, separate generating windings for direct current and high tension ignition current, respectively, and a rotor common to all of said windings and having at one end a flux distributing section for distributing the flux of the field first through and then outside of said high tension generating winding. 110 115

5. In a single unit direct current and high tension ignition current generator, the combination of a unitary field structure, exciting windings therefor, separate generating windings for direct current and high tension ignition current, respectively, and a rotor common to all of said windings and having at one end a flux distributing section for distributing the flux of the field first through and then outside of said high tension generating winding and at its other end carrying the rotatable parts of the direct current generator. 120 125

6. In a single unit direct current and high

130

5 tension ignition current generator, the combination of a unitary field structure, exciting windings therefor, separate generating windings for direct current and high tension 10 ignition current, respectively, and a rotor common to all of said windings, and comprising at one end the rotatable parts 15 of the high tension current generator and at its other end the rotatable parts of the direct 20 current generator.

10 7. In a single unit direct current and high tension ignition current generator, the combination of a unitary field structure, exciting windings therein, separate generating windings therein for direct current and high tension 15 ignition current, respectively, and a shaft rotatably mounted in said field structure and common to all of said windings and carrying iron sections, one of which 20 constitutes a part of the magnetic path for the flux which interlinks with said high tension generating winding and the other of which sections constitutes a part of the magnetic path for the flux interlinking with 25 said direct current generating winding.

8. In a single unit direct current and high tension ignition current generator, the combination of a unitary field structure, exciting windings therein, separate generating windings therein for direct current and high tension 10 ignition current, respectively, and a shaft rotatably mounted in said field structure and common to all of said windings and carrying iron sections, one of which 15 constitutes a part of the magnetic path for the flux which interlinks with said high tension generating winding and the other of which sections constitutes a part of the magnetic path for the flux interlinking with 20 said direct current generating winding, and circuit opening and closing mechanism for said high tension winding actuated by said shaft.

9. A single unit combined direct current 15 and high tension ignition current generator, comprising a unitary field structure, separate generating windings for the direct current and high tension ignition current, respectively, separate exciting windings for 20 the magnetic circuits in inductive relation with said generating windings, respectively, and a shaft rotatably mounted in said field structure and carrying iron sections, one of which sections is disposed to constitute part 25 of the magnetic path for the flux which interlinks with said direct current winding and the other of which sections is disposed to form a part of the magnetic path for the flux which interlinks with said high tension 30 ignition current generating winding.

10. In a single unit direct current and high tension ignition current generator, the combination of a unitary field structure, exciting windings therefor, separate generating windings therein for direct current and

high tension ignition current, respectively, a shaft rotatably mounted in said field structure and common to all of said windings and carrying iron sections which constitute parts of the magnetic circuits for the fields in inductive relation with said generating windings, respectively, and circuit opening and closing mechanism for said high tension generating winding actuated by said shaft. 70

11. In a single unit direct current and high tension ignition current generator, the combination of a unitary field structure, exciting windings therein, a shaft rotatably mounted in said field structure, an armature including a low tension generating winding 80 carried by said shaft near one end thereof, an unwound flux distributor carried by said shaft near its other end, and a normally stationary high tension ignition current generating winding disposed in inductive relation in the magnetic circuit in which said flux distributor operates. 85

12. In a single unit direct current and high tension ignition current generator, the combination of a unitary field structure, a shaft rotatably mounted in said field structure, an armature including a low tension generating winding carried by said shaft near one end thereof, an unwound flux distributor carried by said shaft near its other end, a normally stationary high tension ignition current generating winding disposed in inductive relation in the magnetic circuit in which said flux distributor operates, and separate exciting windings in said magnetic field 100 structure for establishing magnetic flux to interlink, respectively, with said high tension and low tension generating windings. 95

13. In a combined direct current and high tension ignition current generator, the combination of a unitary field structure, an armature shaft mounted near either end in said field structure, a low tension armature carried by said armature shaft near one end thereof, an unwound flux distributor carried 110 by said shaft near the other end thereof, an ignition generating winding disposed in inductive relation to the magnetic circuit of which said unwound flux distributor constitutes the movable part, and separate field 115 exciting windings in said field structure for establishing magnetic flux to interlink with said generating windings, respectively.

14. In a combined direct current and high tension ignition current generator, the combination of a unitary field structure, an armature shaft mounted near either end in said field structure, a low tension armature carried by said armature shaft near one end thereof, an unwound flux distributor carried 120 by said shaft near the other end thereof, an ignition generating winding disposed in inductive relation to the magnetic circuit of which said unwound flux distributor constitutes the movable part, and separate field 125 exciting windings in said field structure for establishing magnetic flux to interlink with said generating windings, respectively. 130

citing windings in said field structure for establishing magnetic flux to interlink with said generating windings, respectively, said exciting winding for the high tension generating circuit being disposed concentric with the axis of said armature shaft.

15. In a combined direct current and high tension ignition current generator, the combination of a unitary field structure, an armature shaft mounted near either end in said field structure, a low tension armature carried by said armature shaft near one end thereof, an unwound flux distributer carried by said shaft near the other end thereof, an ignition generating winding disposed in inductive relation to the magnetic circuit of which said unwound flux distributer constitutes the movable part, and separate field exciting windings in said field structure for establishing magnetic flux to interlink with said generating windings, respectively, said exciting winding for the high tension generating circuit being disposed adjacent to said flux distributer and surrounding said shaft which carries it.

16. In a combined direct current and high tension ignition current generator, the combination of a unitary field structure, an armature shaft mounted near either end in said field structure, a low tension armature carried by said armature shaft near one end thereof, an unwound flux distributer carried by said shaft near the other end thereof, an ignition generating winding disposed in inductive relation to the magnetic circuit of which said unwound flux distributer constitutes the movable part, and separate field exciting windings in said field structure for establishing magnetic flux to interlink with said generating windings, respectively, said exciting winding for the high tension generating circuit being disposed relative to said flux distributer and high tension generating winding so that said flux distributer will always maintain a path of least reluctance for the magnetic circuit in the same electro-magnetic relation to said exciting winding.

17. An ignition system comprising a field structure having a stator, an unwound flux distributer rotatably mounted in said field structure and having its polar faces coöperating with the polar faces of said stator, an ignition current generating winding carried by said stator, and an exciting winding disposed in said field structure to establish therein magnetic flux which interlinks with said generating winding, said stator, flux distributer and exciting winding being shaped and correlated so that in operation said flux distributer will alternately increase and decrease the flux linking through said winding and will maintain the path of least reluctance for the magnetic circuit always

in the same electro-magnetic relation to said exciting winding, whereby the direction of the passage of the magnetic flux between said stator and flux distributer will always be the same.

18. An ignition system comprising a field structure having a stator, an unwound flux distributer rotatably mounted in said field structure and having its polar faces coöperating with the polar faces of said stator, an ignition current generating winding carried by said stator, said stator, flux distributer and generating winding being shaped and correlated so that in operation said flux distributer will alternately increase and decrease the flux linking through said winding and will maintain the path of least reluctance for the magnetic circuit always in the same electro-magnetic relation to said generating winding, and an exciting winding disposed adjacent to said flux distributer and concentric to the axis about which said flux distributer rotates.

19. In a single unit direct current and high tension ignition current generator, the combination of a unitary field structure, exciting windings therein, a shaft rotatably mounted in said field structure, an armature including a low tension generating winding carried by said shaft near one end thereof, a flux distributer carried by said shaft near its other end, and a normally stationary high tension ignition current generating winding disposed in inductive relation in the magnetic circuit in which said flux distributer operates.

20. In a single unit combined low tension current and high tension ignition current generator, the combination of a unitary field structure, a low tension generating winding, a separate high tension generating winding for the ignition current comprising a coarse section and a fine section, electrical exciting means adapted in conjunction with said low tension generating winding to produce in said field structure magnetic fields inductively related to said low tension and high tension generating windings, means for periodically opening and closing the circuit through the coarse section of said high tension winding, and rotatable means inductively related to the said generating windings and adapted in operation to expend mechanical energy in the fields which interlink with the low and high tension generating windings for the production of electromotive forces therein.

In testimony whereof I affix my signature in the presence of two witnesses.

LÉON J. LE PONTOIS.
